UNITED STATES PATENT OFFICE

2,500,429

ELECTRIC GAS BLAST CIRCUIT BREAKER

Hendrik A. Hidde Nijland, Laren, Netherlands

Application February 15, 1946, Serial No. 647,864
In the Netherlands February 19, 1942Section 1, Public Law 690, August 8, 1946
Patent expires February 19, 1962

6 Claims. (Cl. 200—148)

1

This invention relates to improvements in electric circuit breakers particularly of the type in which a gas blast is used for extinguishing the arc between the contacts.

An object of the invention is to provide a construction wherein the pressure of a gas is utilized to initiate the breaking of the circuit and then after the circuit has been broken and the arc extinguished the contacts are separated a safe distance by independently operated means which also close the contacts.

A further object is to provide a construction in which the contacts are in the form of a valve so as to control the outlet for the extinguishing gas.

Another object is to provide a piston which is coupled to one of the electrical contacts only during the time of the initial breaking of the circuit and is uncoupled during the further separation of the contacts and during the closing of the contacts.

A still further object of the invention is to provide a construction wherein the movement of the above mentioned piston is relatively small so that the size of the cylinder containing the arcing chamber is reduced.

A further object is to provide a construction wherein one of the contact elements may be withdrawn or inserted into the circuit breaker while the fixed terminal contacts remain energized and the arcing chamber and piston for initiating the circuit break remain in place.

A still further object is to provide a simplified construction wherein the usual provision of two separate circuit breakers in series is eliminated.

With the above and other objects in view which will become apparent from the detailed description below several preferred embodiments of the invention are illustrated in the drawings, in which:

Fig. 1 is a longitudinal sectional view of a circuit breaker according to the invention with the contacts in closed position.

Fig. 2 is a similar view of a modified construction.

Fig. 3 is a similar view of the construction shown in Fig. 2 with the parts in the position which they occupy after the initial break of the circuit.

Fig. 4 is a similar view of the construction shown in Fig. 2 with the parts in the position which they occupy after the contacts have been moved to a safe distance from one another, and

Fig. 5 is a diagrammatic view with parts in elevation of the complete device illustrating the

2

means for moving the contacts to a safe distance and for closing the contacts.

In the drawings like reference characters refer to like parts in the various figures.

Referring to Fig. 1 a cylinder 1 of insulating material is closed at its lower end by a metal cap which has at its center a fixed contact 2 in the form of a valve seat. A movable rod shaped contact 3 cooperates with the contact 2 and the contact 3 is in permanent sliding contact with the terminal contacts 4 arranged in a circular series. The contact 2 through the metal cap is electrically connected to the terminal ring 7 and the terminal contacts 4 are electrically connected with the terminal ring 8. The rings 7 and 8 are mounted on the casing 5 which is located within the casing 6. The leads 41 and 42 shown in Fig. 5 are connected to the terminal rings.

20 The arcing chamber within the cylinder 1 is closed at its upper end by a cover 9 provided with a conduit 10 whereby gas under pressure may be introduced into the arcing chamber through the ducts 11.

25 When the contacts 2 and 3 are initially separated such gas under pressure will pass at high speed through contact 2 and the arc between contacts 2 and 3 is first directed towards the pin 13 mounted in the center of a funnel shaped gas outlet 12 and then extinguished.

30 Contact rod 3 is secured to an intermediate rod 15 by an insulating tube 14 constituting an extension of contact rod 3. The rod 15 is recessed at its upper end to slidably fit the operating mechanism shown in Fig. 5. The rods 15 and 16 are interconnected by means of a pin 17 fixed to the rod 16 and the slots 18 provided in the rod 15 thereby providing a limited lost motion connection between the rods. A compression spring 19 located within the recess of the rod 15 acting against the end of the rod 16 urges the contact 3 against contact 2 when the circuit is closed.

35 Slidably mounted upon the rod 15 within the cover 9 is a piston 20. Such piston is movable within the cylindrical chamber 21 and is urged downwardly by a spring 22 bearing at one end against the upper surface of the piston 20 and at the other end against the cover 9. The piston 20 is designed to be moved by the pressure of the gas in the arcing chamber when it reaches a predetermined value upwardly as shown in Fig. 1 and on such upward movement the piston will contact a shoulder 23 provided upon the rod 15. The upward movement of the piston

will therefore move the rod 15, the insulating tube 14 and the contact 3 upwardly to bring about the initial breaking of the circuit. The upward movement of the piston is limited by the abutment 24 provided upon the cover 9.

After the initial breaking of the circuit has taken place then the operating mechanism for further separating the contacts comes into action. Such a mechanism is shown in Fig. 5 wherein a pivoted lever 34 is pivotally connected at one end to the rod 16 and at its other end is pivoted to a fixed part upon the circuit breaker. The lever 34 is actuated by means of a piston 35 slidably mounted within a cylinder 33.

The gas for operating the piston 20 and for extinguishing the arc between contacts 2 and 3 when initially separated is supplied from a pressure tank 40. When the circuit is to be broken the valve 37 is opened which permits gas to flow through the conduit 10 to the inside of the circuit breaker through the ducts 11. When the gas reaches a predetermined pressure the piston 20 is moved upwardly which raises contact 3 a short distance from contact 2 breaking the circuit and gas can then escape through contact 2 and extinguish the arc.

At the same time gas will pass through valve 36 and flow to the cylinder 33 to act upon piston 35 which in turn actuates the lever 34 thereby moving the rod 16 upwardly. The rod 16 will then move the contact 3 from its initial separation point to its final position at a safe distance from the contact 2. The valve 36 acts as a throttle so that the operation of piston 35 is delayed with respect to the action of piston 20 which acts immediately. Valve 36 may be adjusted to regulate the delayed action desired.

The lost motion connection between the rods 15 and 16 provided by the pin 17 and the slots 18 permits the contact 3 to be moved a short distance by the piston 20 and thereby bring about the initial separation of contacts 2 and 3 without any movement of the rod 16. The mechanism for breaking the circuit initially is therefore independent of the operating mechanism for moving the contacts to a safe distance from one another and closing the contacts.

In the embodiment shown in Figs. 2, 3 and 4 the piston 20' is slidable upon an enlarged portion 25 constituting an extension of the contact rod 3'. The enlarged portion 25 is above the fixed terminal contacts 4. The upper end of the contact rod 3' is further enlarged so as to form an abutment 23' for the piston 20' and has a recessed sleeve portion 26 therein which slidably engages the plug 27 with a lost motion connection formed by the pin 17' and slots 18'. The plug 27 is secured by an insulating tube 28 to the rod 16. A compression spring 19' is located in the sleeve 26 between the plug 27 and the bottom of the recess.

The cylindrical chamber 28' in which the piston 20' is movable is supported by an insulating tube 29 secured to the cylinder 1. A spring 22' located within the interior 21' of the chamber 28' bears at one end against the piston 20' and at its other end against the top wall of the chamber 28'. The gas from the tank 40 for initiating the breaking of the circuit and extinguishing the arc is supplied through the space between the cylinder 5 and the cylinder 1'. Such gas then passes through the openings 39 provided in the cylinder 1' in order to reach the arcing chamber. The upward movement of the piston 20' is limited by abutment 24'.

The lower end of the chamber 28' is partially closed by a ring member 31 having a central opening whose diameter is less than the diameter of the piston 20'. In the nonoperating position of the piston 20' this opening is closed by a reduced portion 32 upon the piston 20'. The object of this construction will be explained below.

The operation of the circuit breakers described above is as follows:

10 When the contacts 2 and 3 or the contacts 2 and 3' are to be separated, gas under pressure flows into the arcing chamber either through the ducts 11 of the construction shown in Fig. 1 or through the openings 30 in the modification shown in Figs. 2, 3, and 4. As soon as the gas reaches a predetermined pressure in the chamber the piston 20 or 20' is moved upwardly against the pressure of the spring 22 or the spring 22'.

In the circuit breaker as shown in Fig. 1 the rod 15, the insulating tube 14 and the contact rod 3 immediately follow the movement of the piston 20. In the circuit breaker as shown in Figs. 2 to 4 the piston 20' first moves a slight distance freely before abutting the shoulder 23' and moving the contact rod 3'.

In both constructions since the rod 16 at first remains stationary the pressure exerted by the spring 19 or 19' must be overcome before the contact rod 3 or 3' is moved. When the piston 20 or 20' reaches its top position where it engages either the abutment 24 or the abutment 24' the contact rod 3 or 3' is spaced a short distance from the fixed contact 2. See Fig. 3. The circuit is thereby broken and the compressed air in the chamber escapes at high speed through contact 2. The arc drawn by the separation of the contacts is thus first directed towards the pin 13 and then extinguished. Consequently the arc is relatively small.

40 Shortly after the arc has been extinguished and the circuit broken the rod 16 is moved upwardly by the lever 34 and contact rod 3 or 3' is moved a substantial distance from the fixed contact 2 in order to isolate them. See Fig. 4. The circuit is thus definitely broken.

Simultaneously with or shortly after the upward movement of the rod 16 has been completed the supply of gas from the tank 40 is shut off. The closing of the circuit is achieved by moving the rod 16 downwardly and during this operation the piston 20 or 20' is inoperative.

In order to prevent a slow separation of the contacts during the initial separation and thereby causing a wavering in the interruption of the current or preventing a good arc extinguishing action at the moment contact is broken, the construction shown in Figs. 2, 3 and 4 is provided wherein the ring 31 cooperates with the reduced portion 32 of the piston 20' and the piston 20' may move freely a slight distance before contacting the abutment 23'. In this construction the pressure of the gas must reach a predetermined high value in order that the pressure on the reduced portion 32 of the piston 20' becomes sufficient to overcome the action of the spring 19' and thereby move the piston upwardly. However, before the piston contacts the abutment 23' upon the rod 3' the reduced portion 32 will move out of the ring 31 and thereby expose the entire bottom surface of the piston 20' to the high pressure of the gas. This will cause the rod 3' to be moved forcefully and at high speed from contact 2. This brings about an abrupt interruption of the circuit and prevents burning of the contacts.

In the illustrated circuit breakers the rod 16, the contact rods 3, 3' and the interposed connecting parts are arranged in alignment with one another. Also the diameters of the connecting parts have been so chosen that the diameters increase from the bottom upwardly. Therefore due to this construction the contact rod 3 or 3' may be entirely withdrawn from the circuit breaker while the fixed contact 2 and the fixed terminal contacts 4 remain in the circuit breaker.

The embodiment as shown in Fig. 1 has the advantage that the piston 20 and associated parts may be mounted directly on the cover 9 of the circuit breaker so as to have earth potential. On the other hand, however, the piston has to lift not only the contact rod 3 but also the insulating tube 14 and the interconnecting rod 15. In the construction as shown in Figs. 2 to 4 the piston 20' has the same potential as the fixed terminal contacts 4 so that the piston 20' has to be insulated with respect to the earth. An advantage of this construction is that during the breaking of the circuit the piston 20' need only move the contact rod 3' which results in a more rapid interruption of the circuit.

What I claim is:

1. An electric gas blast circuit-breaker comprising an arcing chamber having an inlet and an outlet, a rod-shaped movable contact, a fixed contact cooperating with said movable contact, said movable and said fixed contact being located in said chamber, a source of gas supply under pressure, means connecting said source to said inlet, said movable and fixed contacts forming a valve controlling said outlet so that upon separation of said contacts gas escaping from said chamber through said outlet will extinguish the arc drawn between said contacts, a fixed cylinder having one side in communication with said arcing chamber, an extension upon said movable contact extending through said cylinder, a spring loaded piston slidably mounted in said cylinder and slidably on said extension operable by the pressure of gas entering said chamber, a shoulder on said extension cooperating with said piston to move said extension and said movable contact slightly in one direction to separate said contacts, said piston being independent of said movable contact during all other movements thereof, a stop member arranged in fixed relation to said movable contact engaged by said piston when actuated by said gas to terminate said slight movement which interrupts the electrical circuit and permits the gas to extinguish the arc drawn between said contacts, means connected to said extension of said movable contact operable after the termination of said slight movement for moving said movable contact a further safe distance from said fixed contact and a lost motion connection between said means and said movable contact to permit said piston to separate said contacts by said slight movement without at the same time moving said means for moving said contacts to a safe distance.

2. An electric gas blast circuit-breaker as set forth in claim 1 wherein said extension includes an intermediate rod having said shoulder thereon to one end of which said movable contact is attached through an insulator.
3. An electric gas blast circuit-breaker as set forth in claim 1 wherein said lost motion connection comprises a spring loaded plug- and sleeve-joint.
- 10 4. An electric gas blast circuit-breaker as set forth in claim 1 wherein said extension includes an intermediate rod, said piston being slidably supported on said intermediate rod and said stop member being formed as a shoulder on said cylinder, which is engaged by said piston when the latter is driven by the gas in the switching-off direction.
- 15 5. An electric gas blast circuit-breaker as set forth in claim 1 wherein said piston is slidably mounted on a portion of said extension of said rod-shaped movable contact, spaced terminal contacts connected to said movable and fixed contacts, said portion lying outside the space between said terminal contacts and said portion having said stop member formed as a shoulder, which is engaged by said piston when the latter is driven by the gas in the switching-off direction, and said lost motion connection is constructed as a spring loaded plug- and sleeve-joint.
- 20 30 6. An electric gas blast circuit-breaker as set forth in claim 1 wherein said piston is slidably mounted on a portion of said extension of said rod-shaped movable contact, spaced terminal contacts connected to said movable and fixed contacts, said portion lying outside the space between said terminal contacts and said portion having said stop member formed as a shoulder, which is engaged by said piston when the latter is driven by the gas in the switching-off direction, and said lost motion connection is constructed as a spring loaded plug- and sleeve-joint.
- 25 35 40 45 7. An electric gas blast circuit-breaker as set forth in claim 1 wherein said extension of said movable contact includes an insulator and an intermediate rod, and said circuit breaker includes spaced terminal contacts connected to said movable and fixed contacts, and said movable contact, said lost motion connection, said insulator and said intermediate rod are arranged in alignment with one another and form a composite unit which may be withdrawn from the circuit breaker or inserted thereinto while said terminal contacts remain alive and the cylinder and its piston remain in place.
